CLAIM

The ornamental design for a control console for a mobile telephone with handset, substantially as shown and described.

DESCRIPTION

FIG. 1 is a perspective view of my new design showing the front, top, and left hand side of the control console for a mobile telephone with the handset, showing its back side, and cradled therein.

FIG. 2 is an elevational view of the right hand side of the console with the handset cradled therein.

FIG. 3 is a top end view of the console with the handset cradled therein.

FIG. 4 is a perspective view of front, left hand side and bottom end view of the console with the handset removed from the cradle and resting on its backside.

The telephone cord is shown in broken lines in FIGS. 1 and 4 and fragmentarily in FIG. 2 for ease of illustration.

FIG. 1

FIG. 2

FIG. 3

FIG. 4
